DEFLECTING TOOL

Leonidas C. Miller, Dallas, Tex., assignor of one-half to Eastman Oil Well Survey Company, Dallas, Tex., a corporation of Delaware, and one-half to Eastman Oil Well Survey Corporation, Long Beach, Calif., a corporation of California

Application December 2, 1940, Serial No. 368,132

15 Claims. (Cl. 255—1.6)

This invention relates to new and useful improvements in deflecting tools.

One object of the invention is to provide an improved deflecting tool which is adapted to be lowered into position within a well bore and rotated therein to change the direction or inclination of said bore and being particularly useful in controlled or directional drilling operations.

An important object of the invention is to provide a well bore deflecting tool which is arranged to automatically off-set or incline in a predetermined or known direction within the bore, whereby said tool may be accurately oriented after it has been lowered into the bore to permit drilling in a desired direction to be accomplished.

Another object of the invention is to provide an improved well bore deflecting tool wherein the drill bit of said tool is mounted so as to automatically swing or off-set in a predetermined known direction, together with means for locking the same in such position, whereby a rotation may be imparted to the tool to properly orient the drill bit and dispose the same in the desired direction in which drilling is to be continued.

A further object of the invention is to provide an improved deflecting tool, of the character described, having hydraulically actuated means for locking the drill bit in its deflected position, said means being actuated by the pressure of the fluid which is circulated downwardly through the drill stem and which is normally circulated around the bit during the drilling operation.

Still another object of the invention is to provide an improved valve arrangement for controlling the fluid pumped downwardly through the drill stem to the deflecting tool, whereby said fluid may be directed to the hydraulic locking means for locking the drill bit in a predetermined position prior to the drilling operation; the arrangement being such that after the bit of the deflecting tool has been properly oriented and actual drilling started, the valve is automatically actuated to permit circulation of the fluid through the drill bit and also to the locking means to retract the same.

A particular object of the invention is to provide an improved well bore deflecting tool, wherein in the pilot bit is mounted so as to automatically swing in a predetermined direction when lowered into the well bore; the construction making it possible to cause said bit to swing either to the low side or to the high side of the bore, from which point proper orientation of said bit may be accomplished.

The construction designed to carry out the invention will be hereinafter described together with other features of the invention.

The invention will be more readily understood from a reading of the following specification and by reference to the accompanying drawings, as an example of the invention is shown, and wherein:

Figure 1 is an elevation of a deflecting tool, constructed in accordance with the invention, and illustrating the device lowered within a well bore with the bit swung to the low side of said bore.

Figure 2 is an enlarged, transverse, vertical, sectional view of the deflecting tool, with the hydraulic locking means retracted prior to the orientation of the tool.

Figure 3 is a transverse, sectional view of the hydraulic locking means in a position locking the bit in its deflected position.

Figure 4 is a view, similar to Figure 2 with the parts in their respective position after orientation and during the drilling operation.

Figures 5 to 10 are horizontal, cross-sectional views, taken on the lines 5—5, 6—6, 7—7, 8—8, 9—9 and 10—10, respectively, of Figure 2, and

Figure 11 is a view, similar to Figure 1, illustrating the drill bit deflected in a direction toward the high side of the well bore.

In the drawings, the numeral 10 designates the usual rotatable drill pipe or stem which has an elongate coupling sleeve 11 threaded onto its lower end. The drill stem is adapted to be lowered through the well bore W and has the improved deflecting tool T connected to its lower end by means of the coupling sleeve 11. The deflecting tool includes a main body or housing 12 which is connected to a pilot bit assembly 13 by means of a ball and socket connection 12a and, manifestly, the pilot bit assembly is free to swing with relation to the longitudinal axis of the housing 12 and drill stem 10.

The assembly 13 includes a pilot bit 14 having radially extending cutting blades 15 formed on its outer surface. The body of the bit is preferably bored and is formed with the usual fluid circulating passages 16 which have their lower ends terminating adjacent the cutting blades 15. The bit 14 is connected to the lower end of an elongate tubular stem 17 and the upper end of this stem is threaded into the body 18 of a main cutting bit or reamer. The reamer includes vertically extending cutting blades 19 which project radially outwardly from the body of said reamer a desired distance so that upon rotation of said blades within the formation, a bore of the desired

diameter is drilled. A tubular shank 20 has its lower end threaded into the reamer body 18 and a ball 21 is preferably formed integral with the upper end of this shank. It is preferable that the shank have a general tapered, external surface, being slightly reduced toward its upper end and immediately below the ball 21. An extension 22, which is preferably integral with the ball 21, extends upwardly from said ball and the extreme upper end of the extension is conical as illustrated at 23. An elongate passage or bore 24 extends through the shank 20 and through the ball 21 and the upper end of this passage or bore communicates with a pair of inclined ports 25 which extend radially through the lower portion of the extension 22. In this manner, the area outside of the extension 22 may communicate with the bore 24 through the ports 25 and said bore, in turn, communicates with the bore of the tubular stem 17 and the pilot bit 14.

The ball 21 which is provided at the upper end of the shank 20 fits or engages within a ball socket 26 which is formed within a socket element 27. The ball is retained within the socket 26 by means of a flanged collar 28 which is threaded into the lower end of the coupling element 27. The bore 29 of the retaining collar 28 is flared or tapered complementary to the tapered external surface of the shank 20, and this bore co-acts with the shank to limit the swinging movement of the pilot bit assembly 13 with relation to the socket element 27. Suitable packing rings 30 may be interposed between the socket 26 and the outer surface of the ball 21 and similar rings 31 may be interposed between the retaining collar 28 and said ball. Each of the packing rings 30 and 31 may be exposed to the pressures surrounding the ball and socket, whereby such pressures will urge these rings into a tighter sealing engagement. If desired, ball bearings 32 may be mounted in the upper end of the retaining collar 28, whereby rotation of the ball 21 within its socket is facilitated. The socket element 27 within which the ball is mounted is axially aligned within the well bore W by means of radially extending cutting blades 33 which extend vertically on the outer surface of said element.

For rotatably connecting the socket element 27 with the ball 21 so that a rotation of the element will impart rotation to the ball and thus to the pilot bit assembly, said element is provided with a plurality of inwardly extending pins 34 which are suitably secured within the body of the element. A bearing collar 35 is mounted on the inwardly projecting end of each pin and each collar is disposed within a vertical recess 36 which is formed in the external surface of the ball 21 above the retaining collar 28. The recesses 36 are of a sufficient length with relation to the diameter of the collars 35 to permit the ball 21 to undergo a rotative movement within its socket 26. Thus, the pilot bit assembly 13 may undergo a swinging movement with relation to the socket element 27 but upon a rotation of said socket element, a similar rotation is imparted to the pilot bit assembly through the co-action of the connecting pins 34 and the recesses 36.

The tubular body or housing 12 of the deflecting tool has its lower end threaded onto the upper end of the socket element 27 and said housing extends upwardly from said element. The extreme upper end of the bore of the housing 12 is reduced as shown at 37 and the coupling sleeve 11 which connects the drill stem 10 with the housing slidably extends through this re-

duced portion whereby the lower portion of said sleeve is disposed within the upper end of the housing. For rotatably connecting the sleeve 11 to the housing 12, while permitting a limited sliding movement of said sleeve relative to the housing, said sleeve is formed with a plurality of vertical key-ways 38 in its lower portion. Each key-way 38 is adapted to receive an elongate key 39 which is suitably secured within an opening 40 provided in the upper end of the housing 12. It is noted that the keys 39 may, if desired, be made integral with the wall of said housing. Manifestly, with this arrangement, the coupling sleeve 11 may undergo a limited longitudinal movement with relation to the housing 12 but a rotation of the sleeve will impart a similar rotation to the housing through the co-action of the key-ways 38 with the keys 39.

From the above, it will be seen that the drill stem 10 has a direct connection with the housing 12 through the sleeve 11 and any rotation of the stem will rotate said housing. The lower end of the housing, being threaded onto the socket element 27 will impart a rotation to the socket element and the pin and recess connection between said element and the ball 21 will result in a rotation of the pilot bit assembly. The socket element 27 is provided with an axial bore 41 which extends upwardly from the socket 26 and the upper end of this bore is enlarged and threaded to receive the lower end of an elongate cylinder 42. As is clearly shown in Figure 2, the cylinder 42 is concentric to the housing 12 and is of a smaller diameter than the bore of said housing, whereby an annular space or passage 43 is formed between said cylinder and the wall of the housing. The extreme lower end of the cylinder is provided with inclined ports 44 which establish a communication between this annular passage or space 43 and the interior of the cylinder at its lower end. As illustrated, the inclined ports 44 in the cylinder are adjacent the inclined ports 25 which are formed in the upstanding extension 22 on the ball 21.

The upper end of the cylinder 42 is closed by a flanged head or cap 45 which is threaded into the upper end of the cylinder. The flange 46 of the head has an external diameter substantially equal to the diameter of the housing bore and this flange has an annular packing element 47 mounted therein to provide a seal between the cap and the housing, whereby the upper end of the annular passage or space 43 is sealed off. The upper end of the head or cap 45 is formed with an axial bore 48 which extends downwardly from the top of the head. The lower end of the bore 48 communicates with the annular passage or space 43 through a plurality of radially extending ports 49 which are formed in the head and which are open to the extreme upper end of said passage or space. Communication between the housing above the head or cap 45 and the interior of the cylinder 42 is established through a plurality of vertical passages 50 which are drilled through said head and which are located between the radial ports 49, as is clearly shown in Figure 9.

A hollow piston 51 is reciprocable within the upper portion of the cylinder 42 and this piston has an annular packing sleeve 52 mounted upon and in sealing engagement with the bore of the cylinder. The bottom or lower end of the piston is conical or tapered as indicated at 53 and this tapered portion is adapted to co-act with the conical upper end 23 of the extension 22 on the

ball 21. The piston is normally held in a raised position within the cylinder, as shown in Figure 2, by a coil spring 54 which is confined between the lower end of the piston and an internal shoulder 55 which is formed within the bore of the cylinder. When a fluid pressure is applied to the upper end of the piston through the vertical passages 50, said piston is moved downwardly within the cylinder under tension of the spring 54, such downward movement continuing until the conical lower end 53 of said piston engages the conical upper end 23 of the extension, as shown in Figure 3. So long as the piston remains in its lowered position, it is obvious that a swinging of the extension which is a part of the ball 21 is impossible. Since the ball is directly connected with the pilot bit assembly, it will be obvious that when the piston engages the extension, a swinging of the pilot bit assembly is prevented. Upon a release of pressure from above the piston 51, the coil spring 54 will raise said piston upwardly to its original position (Figure 2), any pressure above said piston escaping through bleeder ports 58 which are provided in the upper end of the cylinder 42.

A tubular valve stem 57 has its lower end threaded into the bore 48 of the closure head or cap 45 and this stem extends upwardly above said head and into the lower end of the bore 11a of the coupling element 11. This tubular stem has its lower end in communication with the annular space 43 between the cylinder 42 and the housing 12, and a plurality of inclined openings 58 are provided in the upper end of the stem so as to establish communication between the bore of said stem and the exterior thereof. A valve sleeve 59 is threaded into the lower end of the bore 11a of the coupling element 11 and this sleeve surrounds the valve stem 57. The lower portion of the sleeve has a packing element 60 mounted within its bore and when the coupling sleeve is in a raised position, as shown in Figure 2, the packing element 60 overlies the openings 58 in the valve stem to close said openings. When the coupling sleeve 11 is moved downwardly with relation to the housing 12, the valve sleeve 59 moves downwardly with relation to the valve stem 57 so as to uncover the openings 58; at the same time, the lower end of the packing element 60 engages the upper end of the head or cap 45, as shown in Figure 4, to overlie and close the vertical passages 50 in said head and thereby cut off communication to the upper end of the cylinder 42. Immediately above the packing element 60, the valve sleeve is provided with a plurality of radial ports or openings 61 which establish a communication between the bore 11a of the coupling sleeve 11 and the upper end of the housing 12 above the head or cap 45. A suitable packing cup 62 may be secured to the underside of the coupling sleeve 11 so as to seal off between said sleeve and the bore of the housing 12.

In the operation of the device, the deflecting tool is lowered into the well bore by means of the drill stem 10 as is shown in Figure 1. During such lowering the housing 12 is maintained in substantial axial alignment with the well bore by means of the cutting blades 33 which are formed on the exterior surface of the socket element 27, the outer edges of said cutting blades engaging and riding upon the wall of the bore. During lowering of the device, the piston 51 within the cylinder 42 is held in its raised position by means of the coil spring 54 and said piston is spaced above the upper end of the exten-

22 which is formed on the ball 21. Due to the ball and socket connection, the pilot bit assembly 13 is permitted to swing with relation to the housing 12 and, manifestly, said assembly will swing in a direction toward the low side of the well bore. Thus, when the lower end of the bore is reached, the pilot bit assembly assumes a position with the pilot bit 14 engaging the low side of said bore, as shown in Figure 1.

10 After lowering of the tool is completed, a fluid pressure is pumped downwardly through the drill stem and such pressure will flow downwardly through the bore 11a of the coupling sleeve and then through the ports or openings 61 in the 15 valve sleeve 59. This fluid pressure will then pass downwardly through the vertical passages 50 in the cap or head 45 and into the upper end of the cylinder above the piston 51. Manifestly, this pressure will force the piston downwardly against 20 the pressure of the spring 54 to the position shown in Figure 3, whereby the lower conical end 53 of the piston will engage the inclined upper end 23 of the extension 22. So long as the piston remains in this position, the pilot bit assembly is 25 locked against a swinging movement with relation to the housing 12 and to the drill stem. Since the pilot bit has automatically swung to a position at the low side of the hole, it is manifest that the engagement of the piston with the extension will lock the bit assembly in its off-set or inclined position.

The pressure is maintained against the piston so as to maintain the pilot bit assembly 13 in its off-set position and the drill pipe and deflecting 30 tool may be lifted and rotated so as to properly orient the pilot bit 14. Since the operator knows that the pilot bit 14 is deflected in a position toward the low side of the hole, it is manifest that by locking said bit in such deflected position, the 35 necessary rotation may be imparted to the drill stem to properly locate the bit in the desired direction.

After the bit has been properly oriented, the 40 entire assembly is lowered so that the bit 14 engages the bottom of the well bore. The weight of the drill stem is then placed upon the deflecting tool and such lowering of the drill stem causes the coupling sleeve 11 to move downwardly with relation to the housing 12, such downward movement being permitted by the key connection between the housing and the sleeve. Downward movement of the coupling sleeve with relation to the housing continues until the parts assume the 45 position shown in Figure 4, at which time the packing element 60 of the valve sleeve 59 secured to the lower end of the coupling 11 strikes the top of the closure head or cap 45. When this occurs, the packing element overlies the vertical passages 50 in the head and shuts off the 50 communication with the upper end of the cylinder 42 above the piston 51. The downward movement of the coupling 11 with relation to the housing 12 causes the valve sleeve 59 which is carried by said coupling to move downwardly on the tubular valve stem 57, whereby the packing element 60 of said sleeve which normally closes the inclined ports or openings 58 in the stem 57 is moved downwardly below said openings so as to uncover the same. When the ports or openings 58 are uncovered, the fluid from the drill stem may pass downwardly through the openings 58, through the stem 57 and outwardly through the inclined ports 49 in the head 45 and into the 55 annular space 43 between the cylinder and the housing. This fluid then flows downwardly

through the annular space and through the inclined ports 44 in the lower end of the cylinder 42, from where said fluid passes through the bore 24 of the ball 21 and shank 20. From the shank, the fluid may pass through the tubular stem 17 and then outwardly through the circulating passages 16 of the pilot bit 14 in the usual manner.

The pressure fluid which is circulated downwardly to the pilot bit 14 also passes into the lower end of the cylinder 42 and will exert a pressure against the underside of the piston 51. This pressure will be added to the pressure of the spring 54 and will cause the piston to move upwardly to its original position, such upward movement being permitted by the bleeder ports 55 so that any pressure within the upper end of the cylinder may bleed into the annular flow passage or space 43.

As soon as the weight of the drill stem is imposed upon the deflecting tool to cause the valve mechanism, which controls the flow of fluid, to shut off flow to the upper end of the piston and direct said flow to the pilot bit 14, the drill stem is rotated and such rotation is imparted through the coupling 11, housing 12, ball and socket and to the pilot bit assembly 13, whereby said bit is rotated to perform the drilling operation.

From the foregoing, it will be obvious that the pilot bit assembly 13 is free to swing with relation to the body or housing 12. By maintaining the housing in substantial alignment with the well bore, the pilot bit assembly will always swing to the low side of the hole, such swinging being caused by gravity. After the bit has swung to this position and is ready to be oriented, a fluid pressure is pumped downwardly through the stem to actuate the piston 51 and lock the pilot bit assembly in its off-set or inclined position. After such locking of the pilot bit assembly, the drill pipe may be rotated to properly orient said pilot bit. When orientation of the bit 14 is completed, it is only necessary to lower the weight of the drill pipe or stem downwardly so as to automatically actuate the control valve mechanism, whereby the fluid which was employed to actuate the piston 51 is directed to the drill bit during the drilling operation.

The form of the invention shown in Figures 1 to 10 is such that the pilot bit assembly automatically swings to the low side of the hole, this being caused by maintaining the housing 12 in substantial alignment in the well bore. It would be possible to permit the pilot bit assembly to swing to the high side of the hole and such an arrangement is shown in Figure 11. In this instance, the vertical blades 33 are omitted from the socket element 27, whereby the housing 12 is permitted to move from side to side within the well bore W. The cutting blades 19 on the reamer 18 are enlarged so that the outer vertical edges of said blades contact the wall of the well bore. With this arrangement, the pilot bit assembly 13 is maintained in substantial axial alignment with the well bore at all times. When the lower end of the well bore is reached, it is obvious that the assembly 13 cannot swing of itself because the blades 19a will prevent such swinging with relation to the housing. However, since there is a space between the wall and the housing 12 and the well bore, said housing may move laterally within the bore. When further downward movement of the bit assembly 13 is prevented, it will be manifest that a shifting of the housing 12 will occur, as shown in Figure 11, and such swinging will be toward the low side of the

hole. Such swinging will result in the bit 14 at the lower end of the pilot bit assembly 13 being swung opposite to the direction of movement of the housing 12, with the result that said bit will move toward the high side of the bore. After the assembly is so swung, the hydraulic piston is actuated to lock the same in its deflected position and orientation of the bit may then be carried out, as above explained.

10 The foregoing description of the invention is explanatory thereof and various changes in the size, shape and materials, as well as in the details of the illustrated construction may be made, within the scope of the appended claims, without departing from the spirit of the invention.

15 What I claim and desire to secure by Letters Patent is:

1. A well bore deflecting tool including, a body adapted to be connected to the lower end of a 20 drill pipe, a drill bit assembly suspended from the body and capable of a free swinging movement relative to the longitudinal axis of the body, whereby when the tool is lowered into an inclined well bore, said bit assembly will swing toward a 25 predetermined direction relative to the direction of inclination of the well bore, and hydraulic means within the body arranged to co-act with the assembly for locking the assembly in its deflected position, whereby the tool may be rotated 30 to orient the same.

2. A well bore deflecting tool including, a tubular body adapted to be coupled to the lower end of a drill stem, a drill bit assembly connected to the lower end of the body by means of a universal 35 knuckle joint so that the assembly may swing relative to the longitudinal axis of the body, whereby when the tool is lowered into an inclined well bore said bit assembly will deflect in a predetermined direction relative to the direction 40 of inclination of the well bore, and means for locking the assembly in its deflected position to permit orientation of said assembly.

3. A well bore deflecting tool including, a tubular body adapted to be coupled to the lower end 45 of a drill stem, a drill bit assembly connected to the lower end of the body by means of a universal knuckle joint so that the assembly may swing relative to the longitudinal axis of the body, whereby when the tool is lowered into an inclined 50 well bore said bit assembly will deflect in a predetermined direction relative to the direction of inclination of the well bore, and hydraulic means within the body arranged to co-act with the bit assembly for locking the same in its deflected 55 position to permit orientation of the same.

4. A well bore deflecting tool including, a tubular body adapted to be coupled to the lower end 60 of a drill stem, a drill bit assembly connected to the lower end of the body by means of a universal knuckle joint so that the assembly may swing relative to the longitudinal axis of the body, whereby when the tool is lowered into an inclined well bore said bit assembly will deflect in a predetermined direction relative to the direction 65 of inclination of the well bore, hydraulic means within the body arranged to co-act with the bit assembly for locking the same in its deflected position to permit orientation of the same, and means for conducting a pressure fluid downwardly through the drill stem and to the hydraulic means for actuating the same.

5. A well bore deflecting tool including, a tubular body adapted to be coupled to the lower end 70 of a drill stem, a drill bit assembly connected to the lower end of the body by means of a universal

knuckle joint so that the assembly may swing relative to the longitudinal axis of the body, whereby when the tool is lowered into an inclined well bore said bit assembly will deflect in a predetermined direction relative to the direction of inclination of the well bore, hydraulic means within the body arranged to co-act with the bit assembly for locking the same in its deflected position to permit orientation of the same, said tool having a flow passage establishing communication between the drill stem and the hydraulic means and also having a second passage establishing communication between the drill stem and drill bit assembly, and valve means for controlling the flow through said passages, whereby pressure fluid from the drill stem may be first conducted to the hydraulic means to actuate the same to permit orientation after which said fluid may be directed to the bit assembly during the drilling operation.

6. A well bore deflecting tool including, a tubular body adapted to be coupled to the lower end of a drill stem, a drill bit assembly connected to the lower end of the body by means of a universal knuckle joint so that the assembly may swing relative to the longitudinal axis of the body, whereby when the tool is lowered into an inclined well bore said bit assembly will deflect in a predetermined direction relative to the direction of inclination of the well bore, hydraulic means within the body arranged to co-act with the bit assembly for locking the same in its deflected position to permit orientation of the same, said tool having a flow passage establishing communication between the drill stem and the hydraulic means and also having a second passage establishing communication between the drill stem and drill bit assembly, and valve means for controlling the flow through said passages, whereby pressure fluid from the drill stem may be first conducted to the hydraulic means to actuate the same to permit orientation after which said fluid may be directed to the bit assembly during the drilling operation said valve means being normally in a position permitting flow of pressure fluid to the hydraulic means and being automatically actuated to direct flow to the bit assembly upon the commencement of the drilling operation.

7. A well bore deflecting tool including, a body, a coupling sleeve rotatively and slidably connected to the upper end of the body and adapted to couple the body to the lower end of a drill stem, a drill bit assembly suspended from the body and capable of a free swinging movement with respect to the body, whereby when the tool is lowered into an inclined well bore said bit assembly will automatically swing in a predetermined direction relative to the direction of inclination of the well bore, means within the housing and actuated from the surface for locking the assembly in its deflected position, whereby said tool may be rotated to orient the same, and means for establishing communication between the drill stem and the bit assembly through the housing for conducting fluid to the bit assembly during the drilling operation.

8. A well bore deflecting tool including, a body, a coupling sleeve rotatively and slidably connected to the upper end of the body and adapted to couple the body to the lower end of a drill stem, a drill bit assembly suspended from the body and capable of a free swinging movement with respect to the body, whereby when the tool is lowered into an inclined well bore said bit assem-

bly will automatically swing in a predetermined direction relative to the direction of inclination of the well bore, means within the housing and actuated from the surface for locking the assembly in its deflected position, whereby said tool may be rotated to orient the same, means for establishing communication between the drill stem and the bit assembly through the housing for conducting fluid to the bit assembly during the drilling operation, and valve means for controlling said flow of fluid to the assembly, said valve means being normally closed and being opened when the coupling sleeve is moved downwardly relative to the housing.

15. 9. A well bore deflecting tool including, a body, a coupling sleeve rotatively and slidably connected to the upper end of the body and adapted to couple the body to the lower end of a drill stem, a drill bit assembly suspended from the body and capable of a free swinging movement with respect to the body, whereby when the tool is lowered into an inclined well bore said bit assembly will automatically swing in a predetermined direction relative to the direction of inclination of the well bore, hydraulic means within the housing arranged to co-act with the bit assembly for locking said assembly in its deflected position, whereby the tool may be rotated to orient the same, the housing having a flow passage establishing communication between the drill stem and the hydraulic means and also having a second passage establishing communication between the drill stem and the bit assembly, and valve means associated with the coupling sleeve and actuated by the movement of said sleeve relative to the body for controlling the flow through the passages.

40. 10. The combination with a drill stem of a deflecting tool rotatably connected to said stem so as to be capable of a limited longitudinal movement with respect to the stem, said tool including, a body, a drill bit assembly swingably connected with the body so as to be deflected in a predetermined direction relative to the direction of inclination of an inclined well bore by gravity, fluid-actuated means for locking the bit assembly in its deflected position, and valve means actuated by the sliding movement between the drill stem and body for controlling the flow of pressure fluid from the drill stem to said hydraulic means.

55. 11. The combination with a drill stem of a deflecting tool rotatably connected to said stem so as to be capable of a limited longitudinal movement with respect to the stem, said tool including, a body, a drill bit assembly swingably connected with the body whereby when the tool is lowered into an inclined well bore, the drill bit assembly is urged toward a vertical position by gravity to deflect the bit with respect to the body and toward the low side of the inclined well bore, fluid-actuated means for locking the bit assembly in its deflected position, the body having flow passages for conducting pressure fluid from the drill stem to the fluid-actuated means and to the bit assembly, and valve means for controlling the flow through said passages, said valve means normally being in a position permitting flow to the fluid-actuated means while the tool is suspended from the drill stem and being automatically moved to a position directing flow to the bit assembly when the weight of the drill stem is imposed on the deflecting tool which causes a limited sliding movement of said stem relative to the tool.

12. A well bore deflecting tool including, a body adapted to be connected to the lower end of a drill pipe, a tool assembly suspended from the body and capable of a universal swinging movement relative to the longitudinal axis of the body whereby when the device is lowered into an inclined well bore the tool assembly is swung by gravity into a predetermined position with respect to the direction of inclination of the well bore, an axial extension on the upper end of the assembly, and hydraulically actuated means normally disengaged from said extension and adapted to co-act therewith to lock the assembly in a deflected position.

13. A well bore deflecting tool including, a body adapted to be connected to the lower end of a drill pipe, a drill bit assembly suspended from the body and mounted to undergo a universal swinging movement relative to the longitudinal axis of the body, whereby when the tool is lowered into an inclined well bore the drill bit assembly will be inclined relative to the longitudinal axis of the body to direct the drill bit into a known direction relative to the direction of inclination of the well bore, and means for locking the assembly in its deflected position to permit subsequent orientation of the bit into a desired direction by imparting a rotation to the tool.

14. A well bore deflecting tool including, a body adapted to be connected to a drill pipe, guide means on the lower portion of the body

5 for axially alining said body and the drill pipe within a well bore, a drill bit assembly connected with the body by a universal connection to permit free swinging of the assembly in all directions with respect to the longitudinal axis of the body, said universal connection allowing the drill bit assembly to swing by gravity toward the low side of the well bore when the device is lowered in an inclined bore, and means for locking the 10 assembly in its deflected position to permit subsequent orientation of the bit by imparting rotation to the drill pipe.

15. A well bore deflecting tool including, a body adapted to be connected to the lower end of a drill pipe, an elongate drill bit assembly having a drill bit on its lower end and having its upper end connected to the body by means of a universal joint, guide means on the upper portion of the bit assembly adapted to engage the wall 20 of a well bore for axially alining the assembly within said bore, the axial alinement of the bit assembly together with the universal connection between the body and assembly causing a deflection of the bit toward the high side of an inclined well bore when the drill pipe and tool are lowered in said inclined bore, and means within the body co-acting with the drill bit assembly for locking the assembly in its deflected position to permit subsequent orientation of the bit by imparting a rotation to the drill pipe.

LEONIDAS C. MILLER.
